HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

ROTARY WEB PRINTING PRESS

Application filed June 21, 1930. Serial No. 462,772.

My invention generally comprises certain improvements in multicolor rotary printing presses whereby a printing mechanism may be employed to print at different distances apart upon a traveling web, according to the length of the sheets which are to be cut from the printed web, said printing mechanism being combined with a constant speed sheet cutting mechanism and a change speed feeding mechanism therefor whereby sheets of different lengths may be cut from the printed web.

My invention further comprises a machine of the above character in which a common means is provided for driving the several mechanisms at predetermined speeds.

My invention more particularly comprises a common driving means, in the present instance an electric motor, having a change speed driving connection with the printing mechanism, a constant speed driving connection with the cutting mechanism and a change speed driving connection with the printed web feeding mechanism for the cutting mechanism.

A practical embodiment of my invention is represented in the accompanying drawings, in which

Figs. 1 and 1^a represent in diagram a side elevation of the machine, the mechanisms being represented in full lines arranged to print considerable distances apart on the traveling web and to cut relatively long sheets from the web, and in dotted lines arranged to print short distances apart on the traveling web and to cut relatively short sheets therefrom;

Fig. 2 represents a detail side view of the change speed drive for the printing mechanism when the small change form cylinders (shown in dotted lines in Fig. 1) are used for printing relatively short distances apart on the traveling web, and

Fig. 3 represents a detail side view of the change speed drive for the printed web feeding mechanism for the cutting mechanism when relatively short sheets are to be cut from the printed web.

The multicolor web printing mechanism is represented as a whole by M-P, the sheet

cutting mechanism by S-C, the web feeding mechanism therefor by W-F and the sheet folding mechanism by S-F.

The printing mechanism herein illustrated is substantially like that which is shown, described and claimed in my copending application filed November 10, 1928, Serial No. 318,507 and a general description only thereof will be made herein.

The impression cylinders 1 and 2 are adjustable in a horizontal plane, each for coaction with two selected change form cylinders. The impression cylinder 1 is shown in full lines as coacting with two large change form cylinders denoted by 3, 4 and in dotted lines as coacting with the two selected small change form cylinders 5, 6. The impression cylinder 2 is shown in full lines as coacting with two selected large change form cylinders 7, 8 and in dotted lines as coacting with the two selected small change form cylinders 9, 10.

The means which I have shown for driving the printing mechanism is as follows:

An electric motor 11 has its shaft 12 provided with a gear 13 which meshes with a gear 14 fast on a longitudinal shaft 15, one end of which is provided with a bevel gear 16 which meshes with a bevel gear 17. This bevel gear 17 is provided with a gear 18 which meshes with a gear 19, the shaft 20 of which is mounted in a rocking support 21. One of a selected group of change gears of different diameters is mounted on the shaft 20. A change gear 22 is used when the large change form cylinders, shown in Fig. 1 are in use and a change gear 23 is used where the small change form cylinders shown in dotted lines in said figure are in use.

Either the change gear 22 or the change gear 23, as the case may be, meshes with the gear 24 of a train of gears 24, 25, 26, 27, 28, 29, the gear 28 being bodily adjustable around the axis of the gear 27 to keep it at all times in mesh with the gear 30 of the impression cylinder 1, and the gear 29 being bodily adjustable around the axis of the gear 27 to keep it at all times in mesh with the gear 31 of the impression cylinder 2.

It will be understood that the two selected

change form cylinders of greater or lesser size are driven from the impression cylinders 1 and 2 in the usual manner.

The web to be printed is fed from the web supply roll 32 in the usual manner between the impression cylinder 1 and its two selected change form cylinders and from thence between the impression cylinder 2 and its two selected change form cylinders, in the present instance for printing the web with four colors on one side thereof. From the printing mechanism the printed web is led to the change speed feeding mechanism for the constant speed cutting mechanism, which mechanisms will be immediately described.

The mechanism for cutting the printed sheets of greater or lesser length from the web is herein shown as comprising a rotary cutter 33 arranged to coat every revolution 20 with a stationary cutter 34 to sever a sheet of a predetermined length fed therethrough. The rotary cutter 33 is shown as driven at a constant speed, as follows:

The shaft 15 which is driven from the electric motor 11 through the gears 13 and 14 is shown as provided at one end with a bevel gear 35 which meshes with a bevel gear 36 on the lower end of a vertical shaft 37, the upper end of which shaft is provided 30 with a bevel gear 38 which meshes with a bevel gear 39 of a cross shaft 40. A gear 41 on the shaft 40 drives through an intermediate gear 42 and the gear 43 on the shaft 44 of the rotary cutter.

35 The change speed mechanism for feeding more or less of the printed web through the cutters every revolution of the cutters for cutting longer or shorter sheets is herein shown as comprising the following elements:

40 A gear 45 on the shaft 40 drives through the intermediate gears 46, 47 a gear 51 carried by a rocking support 48 which may be secured in different adjusted positions by means of a clamp bolt 49 and elongated slot 50 concentric with the axis of said arm.

When a longer sheet is to be cut from the printed web the gear 51 which meshes with the gear 47 is also brought into mesh with a wide faced gear 57 on the shaft 54 of a web feed roll 55. This web feed roll drives the web feed drum 56 through the wide faced gear 57 and gear 58.

When a shorter sheet is to be cut, the gears 53 and 57 are moved laterally to bring the gear 57 out of mesh with the gear 51 and the rocking support 48 is then swung into position to bring the gear 51 into mesh with the gear 53.

Suitable pressure rollers 59 may be employed for holding the web on the feed drum 56, if so desired. A suitable guide 60 directs the web from the feed drum 56 to the sheet cutting mechanism.

I have also shown in the accompanying drawings a sheet folding mechanism which

may consist of the coacting rotary folding cylinders 61, 62, the cylinder 61 being provided with the blade 63 and the cylinder 62 with the folding grippers 64 arranged to coact therewith. Suitable means, not shown herein, may be provided for operating the grippers 64 to deposit the folded sheets on to the delivery point 65.

This folding mechanism is shown as being driven at a constant speed from the cutting mechanism through the train of gears 66, 67 and 68.

A suitable means may be employed for conveying the sheets from the cutting mechanism to the folding mechanism, which means is herein shown as comprising an endless carrier 69 and its coacting pressure rollers 70.

While I have shown the web as arranged to be printed in four colors on one side thereof, it is to be understood that it may be printed in one or more colors, as desired.

While I have shown change form cylinders of two diameters in the accompanying drawings, it is to be understood that these change form cylinders may be of any desired diameter, not necessarily a sub-multiple of the impression cylinders, so that successive printings on the web may be spaced at any desired distance apart, within reasonable limits, to suit sheets of different lengths to be cut from the printed web.

It is furthermore to be understood that the change speed devices for driving the printing mechanism and the web feeding mechanism should correspond to the length of sheets to be cut from the web.

While this invention is suitable for handling webs of any character it is particularly designed for so called bag printing where the printed web, which may be of thin or loosely woven material, such as burlap, will have the successive printings thereon, in one or more colors, spaced at different distances apart so that sheets of varying lengths may be cut from the printed web, folded and thereafter made into bags.

It is evident that various changes may be resorted to in the construction, form and arrangement of the several parts without departing from the spirit and scope of my invention, and hence I do not intend to be limited to the particular embodiment herein shown and described, but what I claim is:

1. In a machine of the character described, a printing mechanism changeable to print upon a traveling web at different distances apart, a sheet cutting mechanism, a web feeding mechanism therefor and a common means having a change speed driving connection with the printing mechanism, a constant speed driving connection with the sheet cutting mechanism and a change speed driving connection with the web feeding mechanism for the sheet cutting mechanism.

2. In a machine of the character described,

a printing mechanism changeable to print upon a traveling web at different distances apart, a constant speed sheet cutting mechanism, a change speed web feeding mechanism therefor, and means for driving the several mechanisms including a motor and a change speed driving connection between the motor and printing mechanism.

3. In a machine of the character described, 10 a printing mechanism changeable to print upon a traveling web at different distances apart, a constant speed sheet cutting mechanism, a change speed web feeding mechanism therefor, and a common means for driving the several mechanisms including a motor and a change speed driving connection between the motor and printing mechanism.

4. In a machine of the character described, 20 a printing mechanism changeable to print upon a traveling web at different distances apart, sheet cutting and folding mechanisms, a web feeding mechanism therefor and a common means having a change speed driving connection with the printing mechanism, a constant speed driving connection with the sheet cutting and folding mechanisms and a change speed driving connection with the web feeding mechanism for the sheet cutting and folding mechanisms.

30 5. In a machine of the character described, a printing mechanism changeable to print upon a traveling web at different distances apart, constant speed sheet cutting and sheet folding mechanisms, a change speed web feeding mechanism therefor, and means for driving the several mechanisms including a motor and a change speed driving connection between the motor and printing mechanism.

40 6. In a machine of the character described, a printing mechanism changeable to print upon a traveling web at different distances apart, constant speed sheet cutting and sheet folding mechanisms, a change speed web feeding mechanism therefor, and a common means for driving the several mechanisms including a motor and a change speed driving connection between the motor and printing mechanism.

50 7. In a machine of the character described, a printing mechanism changeable to print upon a traveling web at different distances apart, a sheet cutting mechanism, a web feeding mechanism therefor, means for driving the several mechanisms including a motor, a change speed driving connection between the motor and printing mechanism, and a change speed driving connection between the motor and feeding mechanism.

60 8. In a machine of the character described, a printing mechanism changeable to print upon a traveling web at different distances apart, a sheet cutting mechanism, a web feeding mechanism therefor, a common means 65 for driving the several mechanisms includ-

ing a motor, a change speed driving connection between the motor and printing mechanism, and a change speed driving connection between the motor and feeding mechanism.

9. In a machine of the character described, 70 a printing mechanism changeable to print upon a traveling web at different distances apart, a sheet cutting mechanism, a web feeding mechanism therefor, means for driving the several mechanisms including a motor, a change speed driving connection between the motor and printing mechanism, a change speed driving connection between the motor and feeding mechanism, and a constant speed driving connection between the motor and the cutting mechanism.

10. In a machine of the character described, 75 a printing mechanism changeable to print upon a traveling web at different distances apart, a sheet cutting mechanism, a web feeding mechanism therefor, a common means for driving the several mechanisms including a motor, a change speed driving connection between the motor and printing mechanism, a change speed driving connection between the motor and feeding mechanism, and a constant speed driving connection between the motor and the cutting mechanisms.

11. In a machine of the character described, 80 a printing mechanism changeable to print upon a traveling web at different distances apart, sheet cutting and sheet folding mechanisms, a web feeding mechanism therefor, means for driving the several mechanisms including a motor, a change speed driving connection between the motor and printing mechanism, a change speed driving connection between the motor and feeding mechanism, and a constant speed driving connection between the motor and the cutting and folding mechanisms.

12. In a machine of the character described, 85 a printing mechanism changeable to print upon a traveling web at different distances apart, sheet cutting and sheet folding mechanisms, a web feeding mechanism therefor, a common means for driving the several mechanisms including a motor, a change speed driving connection between the motor and printing mechanism, a change speed driving connection between the motor and feeding mechanism, and a constant speed driving connection between the motor and the cutting and folding mechanisms.

13. In a machine of the character described, 90 a web printing mechanism, sheet cutting and sheet folding mechanisms, a web feeding mechanism therefor, and a common drive for the said mechanisms including a shaft connecting the printing mechanism with the feeding, cutting and folding mechanisms and a motor for driving the shaft, said shaft having a change speed driving

connection with the printing mechanism, a change speed driving connection with the feeding mechanism, and a constant speed driving connection with the cutting and folding mechanisms.

In testimony, that I claim the foregoing as my invention, I have signed my name this 18th day of June, 1930.

HOWARD M. BARBER.
